FEEDING APPARATUS FOR CHEMICALS

Filed May 13, 1927

Inventor:

Palmer Dorsey,

By
John Howard Melroy
Attorney

UNITED STATES PATENT OFFICE

PARMER DORSEY, OF CHICAGO, ILLINOIS, ASSIGNOR TO THE IMPERIAL BRASS MANUFACTURING COMPANY, OF CHICAGO, ILLINOIS, A CORPORATION OF ILLINOIS

FEEDING APPARATUS FOR CHEMICALS

Application filed May 13, 1927. Serial No. 191,085.

My invention is concerned with certain new and useful improvements in feeding apparatus for chemicals, which I have shown as substituted for a fundamentally different apparatus having the same function in my application, Serial No. 525,566, filed December 29, 1921, for an acetylene generator, in which the feed of the carbide is effected at necessary intervals to maintain the desired pressure, by the gradual rise and sudden fall of a small gas bell through which all the gas being drawn from the generator must pass, the sudden fall being effected by the sudden escape from the bell of the gas under pressure, contained therein when the bell has been raised by the gas pressure high enough to lift its open bottom from the sealing liquid necessarily employed and in which it is ordinarily immersed.

In my improved construction, while still retaining an element rising and falling as before, I simplify its construction and improve its durability in operation by dispensing with the sealing liquid and employing other and different means for permitting the sudden escape of the gas, as will be herein-after fully described and claimed.

To illustrate my invention I annex hereto a sheet of drawings in which the same reference characters are used to designate identical parts in all the figures, in which—

Fig. 1 is central vertical section through the upper portion of an acetylene generator to which my invention has been applied;

Fig. 2 is a central vertical section through the controlling mechanism for the feed, but on a much larger scale; and

Fig. 3 is a detail on an enlarged scale, as seen from line 3—3 of Fig. 2.

10 is the generating chamber of the customary type containing water, into which the carbide is dropped from the carbide holder 11 occupying the upper portion of the cylindrical top 12 of the casing. Secured in 15 one side of the casing beneath the carbide chamber 11 is a pressure regulator 13 containing a diaphragm opposed by a spring and acted on by the pressure of the gas in the generating chamber, so that the position of 20 the rod 14 projecting therefrom and secured

at its outer end to the diaphragm is controlled by the pressure of the gas in the tank 10. This rod 14 is pivoted at its outer end to the lever 15 fulcrumed at 16 in a suitable bearing piece 17 connecting the lower conical wall 18 of the carbide chamber with the lower end of a cylindrical casing 12. The lever 15 has pivoted in its lower end a mushroom valve 19 which cooperates with the circular outlet for the carbide forming the lower end 55 of the cylindrical bottom portion 18, and this valve 19 stands at a distance from the outlet opening which varies with the pressure of the gas in the generating chamber, and it will be understood that the lower the pressure of 60 the gas, the wider the space between the valve 19 and the opening, so that the carbide will escape in greater quantities each time the valve 19 is vibrated, so as to thereby increase the amount of gas generated and thus 65 raise the pressure. When the pressure is high, the valve 19 stands closer to the outlet so that less carbide can escape each time the valve 19 is vibrated. The valve 19 has secured to its under side a rod 20 which extends through the short pipe 21 let into the side of the cylinder 12 and connected to the 70 T 22, which has the short pipe 23 screwed in its upper portion. The upper end of the pipe 23 is screwed into the boss 24 formed on the lower end of the chamber 25, the upper 75 end of which is closed by the head 26 secured thereto by the bolts and nuts 27. An outlet elbow 28 is screwed into the top of the head, and is connected by the pipe 29, elbow 30 and pipe 31, and connection 32 with the top of the gas washing chamber, or "flare-back", 80 33, in which the gas passes through water in the customary manner, and is led therefrom by the outlet pipe 34 to the cutting or welding tool, or whatever apparatus is employed in connection with the generator.

The apparatus thus far described is identical with that shown in my application, Serial No. 124,878, filed July 26, 1926, to 95 which reference is made for a fuller disclosure of the details of construction.

The outer end of the rod 20 passes through the eye 35, constituting the lower end of the vertical rod 36 extending up through the pipe 100

23 and into the chamber 25. The rod 36 has secured on the upper end thereof a piston 37, which I have shown as conveniently fastened in place by being secured on the threaded 5 upper end of the rod 36 and held in place by the nut 38. The piston 37 does not fit snugly enough to entirely prevent the passage of gas between it and the cylinder, and is loose enough so that it can fall freely when 10 the pressure of the gas beneath it is relieved. For this purpose, I employ the valve 39, the lower conical end of which cooperates with the conical seat 40 formed in the aperture 50 extending through the piston. The valve is 15 provided at its upper end with the threaded stem 51 which is guided by passing through the aperture 52 formed in the center of the bracket 53 secured to the top of the piston by the screws 54. To determine the extent 20 to which the valve can fall away from the seat 40 when the gas pressure is released, I employ the nut 55 contacting with the top of the bracket 53 and held in its adjusted position by the lock nut 56.

25 Toward the end of the downward movement of the piston 37, the bottom of the valve 39 contacts with the bottom of the chamber 25, so that the continued downward movement of the piston causes the valve to be seated, and the gas pressure to become again effective on the under side of the piston, and it is also great enough to hold the valve seated until the piston 37, which is raised somewhat 30 gradually due to the leakage around the edges thereof, has risen to the desired height, when the upper end of the valve stem 51 contacts with a suitable abutment, which is preferably a set screw 57 threaded through the cover 26, and secured in any desired adjustment 35 by the lock nut 58 threaded thereon against the top of the cover. It will be understood that when the piston 37 rises until the upper end of the stem 51 contacts with the abutment 57, the valve is opened against the 40 pressure beneath it, and the gas beneath it rushes rapidly through the passage 50, thereby reducing the pressure beneath the piston so that the latter is free to fall and thus vibrate the rod 20 and through it to mushroom valve 19 to cause the feed. To guide the 45 valve, I provide it above the conical seat portion with the vertical ribs 59 cooperating with the sides of the passage 50 to center the valve during its movements.

50 While I have shown and described my invention as embodied in the form which I at present consider best adapted to carry out its purposes, it will be understood that it is capable of modifications, and that I do not 55 desire to be limited in the interpretation of the following claims except as may be necessitated by the state of the prior art.

What I claim as new, and desire to secure by Letters Patent of the United States, is:

65 1. In an apparatus for generating gas, the

combination with a holder for a dry chemical, of a holder for a liquid, a conduit through which the generated gas is delivered, mechanism for feeding the contents from one holder to the other intermittently in small quantities, a cylinder in said conduit, a piston adapted to reciprocate freely in said cylinder and to be moved in one direction by the pressure of the gas passing through the conduit, a valve in the piston held closed as it is moved by the pressure of the gas, an abutment rigidly secured within the cylinder in position to be engaged by the valve to open it at the limit of its movement to release the pressure and permit the piston to return, and connections from said piston to said mechanism so that each time the piston is reciprocated the feed is effected. 70 75 80

2. In an apparatus for generating gas, the combination with a holder for a dry chemical, of a holder for a liquid, a conduit through which the generated gas is delivered, mechanism for feeding the contents from one holder to the other intermittently in small quantities, a cylinder in said conduit, a piston adapted to reciprocate freely in said cylinder and to be moved in one direction by the pressure of the gas passing through the conduit, a valve in the piston held closed as it is moved by the pressure of the gas, adjustable means for regulating the amount of movement given to the valve, an abutment rigidly secured within the cylinder in position to be engaged by the valve to open it at the limit of its movement to release the pressure and permit the piston to return, and connections from said piston to said mechanism so that each time the piston is reciprocated the feed is effected. 90 95 100

3. In an apparatus for generating gas, the combination with a holder for a dry chemical, of a holder for a liquid, a conduit through which the generated gas is delivered, mechanism for feeding the contents from one holder to the other intermittently in small quantities, a vertical cylinder in said conduit, a piston adapted to reciprocate freely in said cylinder and to be lifted by the pressure of the gas passing through the conduit, a valve in the piston held closed as it is raised by the pressure of the gas, an abutment rigidly secured within the cylinder in position to be engaged by the valve to open it at the limit of its upward movement to release the pressure and permit the piston to fall by gravity, and connections from said piston to said mechanism so that each time the piston is reciprocated the feed is effected. 110 115 120

4. In an apparatus for generating gas, the combination with a holder for a dry chemical, of a holder for a liquid, a conduit through which the generated gas is delivered, mechanism for feeding the contents from one holder to the other intermittently in small quantities, a vertical cylinder in said conduit, a piston adapted to reciprocate freely in said 125 130

cylinder and to be lifted by the pressure of the gas passing through the conduit, a valve having its stem extending upward through the piston and its head adapted to be held seated in the bottom of the piston by the pressure of the gas, an abutment rigidly secured within the cylinder in position to be engaged by the valve stem to open it at the limit of its upward movement to release the pressure and permit the piston to fall by gravity, and connections from said piston to said mechanism so that each time the piston is reciprocated the feed is effected.

In witness whereof, I have hereunto set
15 my hand this 29th day of April, 1927.

PARMER DORSEY.
